UNITED STATES PATENT OFFICE

2,463,203

AUDIBLE SIGNAL

Peter C. Reck, Adrian, Mich., assignor, by mesne assignments, to Sperti Faraday Inc., a corporation of Ohio

Application January 8, 1947, Serial No. 720,799

3 Claims. (Cl. 177—7)

1

This invention relates to mountings, especially in establishing a definite tonal response to impacting, even selectively, for different audible signals in predetermined relation.

This invention has utility when incorporated in a multiple bar type of chime, involving inter-related features of the mountings for the bars, in association with resonant chamber carriers and self-retracting non-resonant vibration reacting impactors therefor.

Referring to the drawings:

Fig. 1 is a front view, with parts broken away, of an embodiment of the invention in a two-bar type of chime signal, adapted for different source cut-in switches, which may be from front and rear doors of a dwelling;

Fig. 2 is a side elevation of the unit of Fig. 1, from the right, portions being removed;

Fig. 3 is a partial vertical section lengthwise thru one of the impactor coils and the hammer operable thereby;

Fig. 4 is a portion of an impactor coil mounting bracket, thru which the impactor plunger may operate;

Fig. 5 is a detail view in plan, looking down upon a grommet and its support, in providing a yieldable holder for a chime bar with sound dampening vibration against transmission therethrough;

Fig. 6 is a fragmentary front elevation looking into the grommet mounting of the chime bar of Fig. 5; and

Fig. 7 is a wiring diagram of the impactor control coils as incorporated in the unit of Fig. 1.

The housing

A base member or plate 1 has upstanding side flange portions 2 upon which may be mounted clip brackets 3 by welding thereto on the sides toward each other. Simultaneous with the weld mounting of the brackets 3 upon the flange portions 2, annular flange-carrying resonant chamber sections 4 are also welded to the portions 2. Each section 4 has a port or central opening 5. Snugly slip-fitted to seat thereon is a complementary housing wall outer face 6 with a flange 7 about the flange of the section 4. The resonant chamber is thus completed in the assembly of the portions 6, 7, which may be plated, as with chrome or nickel. It is thus seen that each cup shaped

2

portion 6, 7, provides the outer wall for a resonant chamber having an inner wall or partition section 4.

A claw or angle portion strip 8 may be welded to the inner side of the upper wall 9 of an arc cover plate or shield 10 provided with an inwardly directed side flange portion 11 nesting about the resonant chamber wall outer flange 7. With the plate 1 against a room side wall, and the shield 10 hanging from the upper edge of the plate 1, a lower inwardly arced portion 12 of the shield 10 completes the envelopment of the unit. In practice this shield 10 may be decorative, and is readily detached by swinging the lower portion 12 outward and lifting the portions 8 clear of the upper edge of the base 1.

The chime bars

Removal of the shield 10 exposes a chamber 13 between the flanges 2 having the brackets 3. Chime bars 14, 15, are yieldably supported in this chamber 13 across the openings 5 as ports to the respective resonant chambers of the sections 4, 5, 6, 7.

25 Openings 16 thru the chime bars 14, 15, have rubber grommets 17 therein, with the brackets 3 protruding therefrom in providing vibration transmission dampening mountings for the chime bars 14, 15. Applicant attributes importance to 30 establishing and maintaining tone value relation, especially as between the different chimes of a unit. In a two-bar assembly as herein disclosed, major third interval, or 5:4 ratio is taken, as between the notes C and E, with also C# to F. It 35 is thus seen that for a normal scale with C 261.62 cycles per second, the frequency for E would be 329.88 per second.

Chime bars, deep case-hardened to Rockwell test 60-65, as carburized and water quenched, 40 have been taken at .09" thickness and 1.25" width. For overall length for C note, the bar 15 is 5.875"; and for E note, the bar 14 is 5.125". The center to center spacing between the openings 16 of the bar 15, for appropriate node length 45 is taken as 3.25" for the note C. The openings 16 of the bar 14 for the note E are spaced 2.875". In the disclosure herein, the bars 14, 15, are not horizontal, but suspended. Adopting the support for the C note chime bar as tangent to the upper 50 side of its upper opening 16, and this modified

by the compression of the rubber of the grommet 17, places the operating center of the upper opening 16 at 1.413" down from the top. However, for the higher note E, the compression of the grommet seems to be less a factor to be cured, and there is a more near approach to half diameter locus for the proper node length factor. This determines the spacing of the upper opening center 16 for the bar 14 as 1.289" down from the top. These top portions, as so dimensioned, are in frequency with the tone emanating from the node and accordingly do not react to quench node performance of the bar.

The impactors

Located in the chamber 13 between the chime bars 14, 15, is a minor housing 18, in which are located coils 19, 20, positioned by cadmium plated steel angle brackets 21, 22, having screws 23 assembling the brackets and thus the coils in the shell or housing 18. Axially extending to protrude both ways from each coil 19, 20, is a brass guide or tube 24. The coils 19, 20, have insulation end disks 25 spacing the magnetizable brackets 21, 22, from the windings of the respective coils. A solenoid core plunger magnet 26 has a plastic hammer or stem 27, projecting from the end of the coil. This normally projecting non-magnetic extension has its end embedded in the end of the core 26. The other end of the core 26, at non-energized position therefor, is laterally from its coil and in the guide 24 to protrude outward therefrom, say away from the bar 14 and toward the bar 15.

It is the purpose to have the plunger or core 26 of a length only slightly exceeding the length of its coil 19, or 20. An aluminum extension 28 provides a non-magnetic additional length terminally to receive, as to the coil 19, a cellulose acetate tip 29 or other suitable plastic embedded therein, as the striker portion of the hammer for the chime bar 15. A tension helical spring 30 is anchored in a groove of the portion 28 adjacent the tip 29 and encircling the portion 28. The protruding portion of the core 26 and the sleeve 24 are outward from the bracket 22 as to the coils. The opposite end of the spring 30 from the portion 28 rests upon the bracket 22. Upon energizing either coil 19, 20, the tip 27 for the plunger 26 in such coil, effects compression of the spring 30 as the chime bar 14 is struck. The recovery therefrom, as to the coil 19, is an impacting of the chime bar 15 by the tip 29. Upon de-energizing of the coil 19, the spring 30 retracts the tip 29 clear of the bar 15, but with the major extent of the core 26 in that portion of the sleeve 24 away from the coil 19, and protruding even beyond the sleeve 24.

In the matter of the plunger 26 in the coil 20, in lieu of the selected plastic tip 29, there is here a sponge rubber tip 31, as a dampener against transmission of impact vibration to or from the chime bar 15. Practically, this means that upon energizing of the coil 19, there is a two-tone audible signal, harmonious in a major third interval. While, upon energizing of the coil 20, there is in response but a single tone or note, that of the bar 14. As with the plunger 26 in the coil 19, this plunger 26 in the coil 20, at de-energizing of the coil 20, has an idle position clear for each of its tips 27, 31, to be away from the bars 14, 15.

Hum or impactor tonal disturbance of the signal is rendered negligible by the temporary magnetic influence of the brackets 21, 22. With a

clearance region 32 above a seat 33 for the sleeve 24, the magnetic flux is unbalanced. The lower side of the plunger 26 has magnetic circuit therefrom to the bracket seat 33. This downward magnetic flux supplements the weight or gravity of the plunger and tends to defeat floating chatter.

The electric circuit

10 Sixty cycle one hundred twenty volt alternating electric current supply lines 34, 35, are to a transformer 36 to step down the voltage into the range of six to eight volts, as a normal house signal circuit. A conductor 37 from the transformer 36 extends to a terminal 38 at a lower portion of the housing 18 in the chamber 13. Leads 39, 40, from the terminal 38, connect respectively to the coils 19, 20. From the other side of the transformer 36, a line 41 extends to a push button switch 42 having a connection by a line 43 to a terminal 44 at the housing 18 for a lead 45 therefrom to the coil 19. Additionally, from the line 41 is a switch 46 in a line 47 to a terminal 48 at the housing 18. From the terminal 48, a line 49 extends to the coil 20. In practice, say for residence audible signal purposes, a switch 42 may be for the front entrance, which, as operated, energizes the coil 19, for the striker therein to impact both chime bars 14, 15, for a two-tone major third interval harmonious sounding of notes. For the purpose of enabling one to locate different sources of calling, the rear entrance of the home may have a second switch 46 for sounding a single note. The closing of the switch 46 does not disturb the coil 19 nor its plunger, but acts solely upon the coil 20. While the striker in the coil 20 has freedom for reciprocation, its deadened end or tip 31 as toward the chime bar 15, nullifies any impact at this region. The result is that the plunger tip 27 strikes the bar 14 for a single distinctive note to be sounded. The householder is thereby enabled readily to detect the call for attention is from the rear door. The springs 30 render the plungers or strikers self-resetting to an idle, floating non-contacting position as to the chime bars 14, 15, once the actuating switch is released.

What is claimed and it is desired to secure by Letters Patent is:

50 1. An audible signal unit comprising a base plate vertical back having a pair of side flanges leaving an upwardly open channel, each of the flanges having mounted thereon an outwardly flanged chamber section, complementary chamber sections telescoped thereon to form outwardly from the respective flanged chamber sections a resonant chamber between the flanged section and the relatively telescopic section, in said channel between the side flanges a pair of suspended chime bars, one in proximity to each resonant chamber, a shield for the bars, carried by the base plate and nesting over the resonant chambers, and horizontally reciprocable electromagnetic strikers for the bars.

55 2. For an audible signal actuator embodying means to be impacted, said actuator comprising an alternating electric current energizing source, a coil to be energized, a plunger in the coil to act upon the means to be impacted, magnetic material end means for the coil having lateral air gap upward from the plunger in providing downward flux to supplement gravity in stabilizing the plunger from hum generating floating movement, otherwise tending to arise due to harmonics from the current.

60 3. For an audible signal actuator embodying means to be impacted, said actuator comprising an alternating electric current energizing source, a coil to be energized, a plunger in the coil to act upon the means to be impacted, magnetic material end means for the coil having lateral air gap upward from the plunger in providing downward flux to supplement gravity in stabilizing the plunger from hum generating floating movement, otherwise tending to arise due to harmonics from the current.

65 4. For an audible signal actuator embodying means to be impacted, said actuator comprising an alternating electric current energizing source, a coil to be energized, a plunger in the coil to act upon the means to be impacted, magnetic material end means for the coil having lateral air gap upward from the plunger in providing downward flux to supplement gravity in stabilizing the plunger from hum generating floating movement, otherwise tending to arise due to harmonics from the current.

70 5. For an audible signal actuator embodying means to be impacted, said actuator comprising an alternating electric current energizing source, a coil to be energized, a plunger in the coil to act upon the means to be impacted, magnetic material end means for the coil having lateral air gap upward from the plunger in providing downward flux to supplement gravity in stabilizing the plunger from hum generating floating movement, otherwise tending to arise due to harmonics from the current.

75 6. For an audible signal actuator embodying means to be impacted, said actuator comprising an alternating electric current energizing source, a coil to be energized, a plunger in the coil to act upon the means to be impacted, magnetic material end means for the coil having lateral air gap upward from the plunger in providing downward flux to supplement gravity in stabilizing the plunger from hum generating floating movement, otherwise tending to arise due to harmonics from the current.

3. An audible signal comprising in horizontal assembly a resonant chamber means, a chime bar, a striker, a second chime bar, therebeyond a second resonant chamber means, a shield spanning the chambers to bridge therebetween and enclose the bars and strikers, said striker including a pulsating electric current energized coil, a plunger core magnet, and magnetic guide brackets therefor having upper side airgap clearance for unbalancing magnetic flux to supplement gravity in quenching pulsation harmonic hum from the magnet.
